MACHINE FOR SORTING COMPRESSIBLE ELEMENTS

Louis M. Puster and John A. Kaserman, Knoxville, Tenn., assignors to Robertshaw-Fulton Controls Company, a corporation of Delaware

Application January 27, 1947, Serial No. 724,530

32 Claims. (Cl. 209—79)

1

This invention relates to automatic sorting machines, and more particularly to a machine for automatically sorting compressible elements according to their varying capacity to resist compression under predetermined loads. While, as will be apparent to those skilled in the art from the ensuing disclosure, the present invention may be applied to machines for automatically sorting a wide variety of compressible elements, it will be exemplified herein by its application to the so-called weighing of expandible and collapsible corrugated tubular walls or bellows, the term "weighing" as used in the bellows art connoting the units of weight or pressure, for example ounces, required to compress a bellows a predetermined amount from its free length, and, when applying a predetermined stroke or load to a bellows, the terms "underweight" and "overweight" being used to denote a resistance to compression or flexure of the bellows which is respectively less than or more than the required minimum and maximum response of such a bellows for that load or stroke, and obviously the same terms can be applied and are herein used in measuring the compressibility of other suitable elements.

To meet the specifications of various uses to which bellows are put, it is necessary that the magnitude of the compression of the bellows from free length under a predetermined load be kept closely within narrowly fixed limits. To sort bellows, the magnitude of compression of which from free length under a given predetermined load falls within such predetermined limits, from those bellows whose magnitude of compression is above or below the upper or lower limits so fixed, it has heretofore been the practice to weigh the bellows on standard weighing scales provided with a hand-operated mechanism for imposing a predetermined load or stroke on the bellows. As the load or stroke has to be controlled closely within narrow limits and the response of the bellows accurately determined, this method of sorting bellows is not only slow, tedious and exacting but it also introduces a factor of human error with not infrequent inclusion of bellows as satisfying certain specifications when they do not.

It is an object of this invention to provide an automatic sorting machine which eliminates the factor of human error in determining whether or not the elements being sorted come within the upper and lower limits fixed by definite specifications.

Another object of this invention is to provide a device of the type characterized wherein, once the machine is set, the sorting of the elements

proceeds automatically without further dependence on an operator as to the making or observing of measurements.

Another object of this invention is to provide a device of the type characterized wherein the elements to be sorted are automatically separated into three groups depending upon whether their characteristics fall within the upper and lower limits set by the specifications, or whether they have characteristics which are respectively above or below the upper or lower limits of the specifications.

Another object of this invention is to provide a device of the type characterized which enables the elements being sorted to be separated into their aforesaid separate classes at a relatively high speed, but with entire accuracy and certainty with respect to their compression response under an automatically predetermined load.

Another object of this invention is to provide a device of the type characterized which can be operated by relatively unskilled labor whose function is solely to locate the elements to be sorted in proper relationship to the machine, whereupon the sorting is effected automatically without further intervention by the operator.

Another object of this invention is to provide a device of the type characterized which is composed of parts that are relatively inexpensive to manufacture, assemble and service and which is highly sensitive, accurate and efficient in performing its sorting action.

Other objects will appear as the description of the invention proceeds.

The invention is capable of receiving a variety of mechanical expressions only one of which has been illustrated on the accompanying drawings, and therefore it is to be expressly understood that the drawings are for purposes of illustration only, and are not to be construed as a definition of the limits of the invention, reference being had to the appended claims for that purpose.

Referring in detail to the drawings wherein corresponding parts are designated by like reference characters in the several figures,

Fig. 1 is a side elevation of a machine embodying the present invention;

Fig. 2 is a plan view of said machine;

Fig. 3 is a perspective view of certain parts of the operating mechanism of the machine;

Fig. 4 is a fragmentary plan view of the automatic stop mechanism for predetermined the extent of stroke of the sorting arm;

Fig. 5 is in part an axial section of the actuating mechanism for the sorting arm;

Fig. 6 is a fragmentary schematic detail of the

operating means for the automatic stop mechanism shown in Fig. 4;

Figs. 7 and 7a are respectively elevations, partly in section, of an automatic switch mechanism and the mechanism operated thereby for locating the index pins which actuate the stop mechanism;

Fig. 8 is a fragmentary elevation of the orifice device;

Fig. 9 is a section on line 9—9 of Fig. 8;

Fig. 10 is a fragmentary bottom plan view of the orifice device of Figs. 8 and 9;

Figs. 11 and 12 are sectional elevational views of the mechanism for effecting the weighing stroke before and after said stroke has been made;

Fig. 13 is a fragmentary perspective view to illustrate the relationship of the solenoid mechanism to the index pins and the lever actuated thereby;

Fig. 14 is an enlarged perspective elevation of the mechanism for effecting the weighing stroke;

Fig. 15 is a fragmentary perspective view to illustrate the relationship of the sorting arm to the outfeed mechanism for conveying the sorted elements from the machine; and

Fig. 16 is a fragmentary plan view of the mechanism carried by the sorting arm for gripping the elements to be sorted.

Summarized generally, a machine embodying the present invention includes an indexing device on which the elements to be sorted, as bellows, are to be disposed, said indexing device being intermittently driven to advance the elements on said tables into and out of a weighing position wherein the compressibility of said elements from their free length under a predetermined load is determined by fluid operated devices that, in response to the variable opposition to compression offered by the elements being measured, effect the displacement of index pins associated with the respective elements, whereby said index pins, when said indexing mechanism advances the weighed elements into a sorting position, set automatic stop mechanism so that an automatically operated sorting arm for removing said elements moves to positions determined by said automatic stop mechanism wherein said elements are deposited on appropriate outfeed conveyors for separating said elements according to the characteristics determined by the weighing mechanism. Thereby, without intervention of the operator, the characteristics of the elements are automatically determined and said elements are sorted according to whether such characteristics fall between specified upper and lower limits, or are above the upper limit or below the lower limit.

In the form shown, the indexing device takes the form of a rotatable turntable 10 carried by a suitable spindle 11 supported in any suitable way in framework carried by the base 12 of a suitable housing 13 for containing the driving mechanism of the machine to be described. Carried by or attached to the underside of said table 10, and concentrically arranged therewith, is a disk 16 (a fragment of which is shown schematically in Fig. 3) provided with upstanding pins 17 whose number corresponds to the number of weighing disks hereinafter described. Disk 16 with its pins 17 constitutes the driven element of a Geneva mechanism of any suitable character, the driving disk 18 of which, with its slot 19, is shown schematically in Fig. 3. Disk 18 is mounted on a suitable stub shaft 20 supported

in any appropriate way by the framework. Shaft 20 is shown as provided with a beveled gear 22 with which meshes a beveled pinion 23 carried by a shaft 24 extending from a speed reducing mechanism 25 of any suitable character and construction, the details of said speed reducing mechanism being omitted in the interest of clearness. Speed reducing mechanism 25 is driven in any suitable way, as by a pulley 26 mounted on the driving shaft 27 of said speed reducing mechanism, pulley 26 in turn being shown as driven by a belt 28 from an electric motor 29 of any suitable form carried by the base 12, the circuit of said motor including a switch 30 (see Figs. 1 and 2) conveniently located on the top member 31 of the housing 13. Any other suitable driving mechanism for the indexing device may be used if preferred.

Table 10 carries any suitable number, here shown as six, weighing disks 35. As shown more particularly in Figs. 11 and 12, each of said disks 35 is provided with a downwardly extending hub 36 loosely received in an aperture 37 provided in the table 10, and each of said disks preferably has its upper face provided with a plurality of concentric grooves 38 of such diameter that they are appropriate to receive and center bellows 39 of different diameters. When each disk 35, under the intermittent rotation of the table 10 by its aforesaid Geneva driving mechanism, arrives at that station which is herein designated the weighing station, its hub 36, which is provided with a conically shaped recess 40, is brought into alignment with the conically shaped upper end 41 of an arbor 42 carried by a slide 43 (see Fig. 14) that may move upwardly and downwardly in suitable ways 44 provided in the framework of the machine. Slide 43 is provided with rollers 45 between which is disposed a cam 46 mounted on a shaft 47 which may be driven in any suitable way from the motor 29 but here shown (see Fig. 3) as provided with a beveled gear 48 that is in mesh with a beveled pinion 49 on a second shaft 50 extending from the speed reducing mechanism 25. Therefore, under the action of said cam 46 the arbor 42 is elevated from the position shown in Fig. 11 to the position shown in Fig. 12 picking up the weighing disk 35 in alignment therewith and moving the bellows 39 on said disk into cooperative relationship with the weighing stroke mechanism or so called "weighing head" to be described.

Referring again to Figs. 11 and 12, each weighing disk 35 when it reaches the weighing station 55 is aligned with a weighing head shown as composed of a rectangular frame having side members 55 and 56 and upper and lower end members 57 and 58 attached to said side members in any suitable way. Slidably mounted on said side members 55 and 56 intermediate of the length thereof is a transverse member 59 normally held against stop members 60, suitably attached to said members 55 and 56, by coil springs 61 shown as surrounding said side members and reacting between the end member 58 and said intermediate member 59. Intermediate member 59, however, may yield downwardly as viewed in Figs. 11 and 12, against the tension of the springs 61, as hereinafter described. Mounted on said intermediate member 59 is a tubular member 62 constituting a housing for the collet mechanism next to be described. Tubular member 62 has a flanged extremity 63 whereby it may be locked in position on the intermediate member 59 by a lock nut 64 received on the exteriorly threaded

surface of said tubular member 62. Member 62 has therein upper and lower chambers 65 and 66 separated by an apertured wall portion or partition 67. Slidably mounted in the chamber 66 is a tubular collet element 68 whose lower beveled extremity 69 cooperates with the gripping elements 70 of the collet mechanism. Slidably mounted in the control aperture of said gripping elements is a spindle 71 having at its upper extremity a head 72 of such size as to prevent the spindle 71 from falling below that position in which the head 72 engages the inner extremity of the gripping elements 70. At its opposite extremity spindle 71 has suspended therefrom, preferably by a ball and socket joint at 73, a disk 74 adapted to be engaged by the upper end of a bellows 39 when lifted by arbor 42 from the position shown in Fig. 11 to the position shown in Fig. 12. The elements of the collet mechanism are secured in position by a tubular nut 75 having an aperture 76 through which the spindle 71 slidably extends.

Tubular element 68 of the collet mechanism is attached in any suitable way, as by a threaded connection, to a rod 77 projecting through the aperture in the wall 67 and in turn attached in any suitable way at its upper end to a piston 78 carrying a cup washer 79 and clamping member 80. As shown, rod 77 has an enlargement 81 against which the piston is locked by a nut 92 and between said enlargement and the wall 67 reacts a coil spring 82 that normally urges the piston 78 upwardly as viewed in Figs. 11 and 12. Piston 78 is mounted in a cylinder 83 of any suitable construction, here shown as in the form of a cup carried by a threaded stud 84 which extends through an aperture in the upper element 57 of the framework and is secured thereto by means of a nut 85. Stud 84 is provided with a passage 86 therethrough in communication with the interior of the cylinder 83, and it has an interiorly threaded socket 87 which receives a suitable connector 88 for a fluid-pressure line 89 hereinafter referred to.

Tubular member 62 is also provided with adjustable stop mechanism for cooperation with the lower member 58 of the framework. As here shown, a disk 90 is threadedly mounted on the threaded exterior surface of said member 62, and a second locking disk 91 is similarly mounted for cooperation with the disk 90 to lock the latter in its adjusted position. The distance between the under face of the disk 90 and the upper face of the end frame member 58 predetermines the weighing stroke of the weighing head, and by suitably adjusting disk 90 with respect to end member 58 the magnitude of this stroke can be nicely and exactly predetermined.

When a weighing disk 35 is elevated by arbor 42 at the weighing station the upper end of the bellows 39 engages the disk 74 and slides the spindle 71 upwardly into the collet mechanism as shown in Fig. 12. Owing to the ball and socket joint 73 the disk 74 is universally mounted so as to make flat true contact with the end of the bellows 39. The extent to which the spindle 71 is slid inwardly with respect to the collet mechanism will vary from bellows to bellows depending upon the free length thereof, and thereby the weighing stroke and the measurement made as a result thereof is independent of such variations as may exist in the free length of the bellows being measured.

When the bellows has reached its uppermost position as shown in Fig. 12, fluid pressure, pref-

erably compressed air of predetermined pressure, is admitted through the line 89, connector 88 and passage 86 to the interior of the cylinder 83, causing piston 78 to move downwardly against the tension of the spring 82. The first downward movement of the rod 77 under the action of piston 78 causes collet member 68 to slide downwardly and actuate the gripping elements 70 so as to lock the spindle 71 in the position to which it has been raised by the bellows 39. Thereafter, further downward movement of the piston 78 is transmitted to the intermediate member 59 which slides downwardly on the side members 55 and 56 against the tension of the springs 61 until stop disk 90 engages the lower member 58 of the framework. Thereby a compression stroke, predetermined by the distance between the underface of the locking disk 90 and the upper face of the member 58, is imparted to disk 74 and therefrom to the bellows 39. The resistance which the bellows 39 opposes this compression stroke of predetermined magnitude is a measure of the compressibility of the particular bellows, and this resistance, in turn, is utilized to determine whether the particular bellows being measured falls within the category wherein its compressibility from free length under the predetermined load is between specified upper and lower limits, or whether the bellows falls into one or the other of the two categories wherein the compressibility under these conditions exceeds the upper limit or is less than the lower limit specified.

The weighing head as so far described is pivotally mounted at its upper and lower extremities on a pair of levers which are so constructed and arranged as to constitute a parallel linkage mechanism whereby the weighing head is always retained in a vertical position in alignment with the bellows on the weighing disk at the weighing station. The upper lever of this linkage mechanism constitutes a counterweight system for balancing the weight of the weighing head and the scale mechanism associated therewith, and the lower lever of this mechanism constitutes the actuator of a scale system as will now be made to appear. Referring particularly to Fig. 14, the upper member 57 of the framework of the weighing head is provided at its opposite extremities (see also Figs. 11 and 12) with spindles 93, preferably received in antifriction bearings 94, carried by the bifurcated extremities 95 and 96 of a lever 100 pivoted at 97, preferably by means of antifriction bearings, on a tubular member 98 carried by a column 99 which may be supported in any suitable way from the housing 13. The bifurcated extremities 95 and 96 are brought together and suitably united beyond the tubular member 98 and there provided with one or more suitable counterweights 101 and 102 adjustably mounted thereon and secured in position in any suitable way, one of said weights as 102 preferably being provided with a vernier adjustment so that the counterbalancing weights may be nicely adjusted to exactly balance the weight of the weighing head and the scale mechanism actuated thereby.

The opposite extremities of the lower member 58 of the weighing head are similarly provided with oppositely-extending spindles 103, preferably received in antifriction bearings 104, carried by the bifurcated extremities 105 and 106 of a scale lever 109 pivoted at 107, preferably by means of antifriction bearings, on said tubular member 98, said bifurcated extremities 105 and 106 being brought together and suitably united beyond the

tubular member 98 to provide the scale lever 109. The opposite end of scale lever 109 has pivoted thereto, preferably by an antifriction bearing at 110, a link 111 which in turn is, pivotally connected at 112, preferably by an antifriction bearing, to a second scale lever 113 pivoted at 114, preferably by an antifriction bearing, on the depending extremity 115 of a bracket arm 116 extending from the tubular member 98. The opposite or inner extremity of scale lever 113 has pivotally attached thereto the rod 114' of a dash pot mechanism 115' which operates to dampen the movement of the inner extremity of scale lever 113 so as to prevent hunting movements thereof. Adjacent the inner end of said scale lever 113 is an anvil member 117 adjustably mounted thereon but suitably fixed thereto, as by set screws 143, for cooperation with the orifice device hereinafter described. The dash pot mechanism 115' may be mounted on a suitable bracket extending from the tubular member 98 and said bracket is also shown as provided with an adjustable stop screw 118 to predetermine the extent of movement of the lever 113 in a clockwise direction around its pivot 114. Scale lever 109 is also shown as provided with a weight pan 119 suspended by rod 120, so that by placing predetermined weights on the pan 119 the weighing mechanism may be exactly adjusted as herein-after referred to.

Tubular member 98 is slidably mounted on the column 99 so that the weighing head with its counterweight and scale levers, with the orifice device and associated parts to be described, can be moved up and down on said column 99 to adjust the weighing head for cooperation with bellows of different lengths. To this end, a rotatable screw 121 is mounted on the housing 13 parallel and closely adjacent to the column 99 and cooperates with a nut carried by said tubular member 98. The upper end of the screw 121 is provided with a manually operable member 122 whereby when rotated in the appropriate direction the tubular member 98 may be caused to slide upwardly or downwardly on the column 99, after which the tubular member may be locked against displacement on the column 99 by any suitable device.

Mounted on the bracket arm 116 in alignment with the anvil member 117 is an orifice device 125 indicated generally in Fig. 1, and shown in detail in Figs. 8 to 10, said orifice device being adjustably located on said bracket arm but fixed thereto in any suitable way, as by set screw 126. Orifice device 125, as shown more particularly in Fig. 9, comprises a body member 127 recessed interiorly to provide a chamber 128 and a second chamber 129, here shown as of larger cross section than chamber 128, said two chambers being separated by a partition 130 having an interiorly threaded aperture therethrough. Mounted in said last named aperture is a member 131 having a passage 132 therethrough terminating in a small orifice 133, said member 131 taking the form of a screw which may be seated against the partition 130 with interposed packing 134. The ends of the chambers 128 and 129 opposite from the partition 130 may be closed in any suitable way as by screws 135 and 136 threaded into the ends of said recesses with interposed packing at 137. A threaded aperture 138 leads from the exterior of the body member 127 to the chamber 128, and threadedly mounted in said aperture 138 is an orifice member 139 having a passage 140 extending therethrough and leading to an external opening 141 which is opposed to the upper

face 142 of the anvil member 117. Communicating with the chamber 129 is a line 144 for conveying fluid under pressure thereto, preferably compressed air of predetermined pressure, while from chamber 128 a pair of back pressure lines 145 and 146 lead therefrom for purposes to be explained.

Fluid under pressure entering the chamber 129 by way of the line 144 may flow through the orifice 133 to the chamber 128 wherein, by predetermining the size of the orifice 133, the pressure can be closely predetermined. From chamber 128 the fluid under pressure escapes through passage 140 and orifice 141, the drop in pressure in chamber 128 because of the escape of fluid through orifice 141 depending upon the spacing of the surface 142 of anvil member 117 from said orifice 141.

The before-referred to resistance to compression of the bellows 39, when the weighing head applies the weighing stroke thereto as heretofore described in conjunction with Figs. 11 and 12, is productive of a small movement of the scale lever 109 around its axis 107, the magnitude of this movement being very slight, on the order of .0002 inch for maximum stroke. Obviously the magnitude of this movement is exactly proportional to the resistance to compression offered by the bellows being weighed. The movement of the scale lever 109 is magnified by the scale lever 113, and as each of said levers 109, 113 moves anticlockwise with respect to their axes, the anvil member 117 is thereby approached toward the orifice 141 by an amount which is exactly commensurate with the resistance to compression of the bellows 39, this movement being rendered dead beat by reason of the dash pot 114', 115'. Approach of the anvil surface 142 toward the orifice 141 accordingly diminishes the escape of fluid from the chamber 128 proportionally to the resistance to compression of the bellows 39 whereby the back pressure developed in chamber 128 is exactly in proportion to such resistance to compression.

The back pressure so developed in chamber 128 is utilized for two purposes. Also mounted on the bracket arm 116 and adjustable with respect thereto but fixed to the bracket arm in any suitable way as by one or more set screws 150 is a bracket member 151 to which is secured the stationary end wall of a small expandible and collapsible chamber or bellows 152 having its movable end wall provided with a contact member 153 which is in contact with the upper face of the scale lever 113 at a point intermediate the axis 114 and the location of the anvil member 117, preferably relatively adjacent to the axis 114. Back pressure line 146 leading from chamber 128 is in communication, in any suitable way, with the interior of the bellows 152, so that the back pressure developed in chamber 128 is applied through the expandible and collapsible chamber 152 to the scale lever 113 at a leverage with respect to the axis 114 which is less than the leverage of the anvil member 117. Thereby variations in the back pressure in the chamber 128 are applied as a counterpoise through the expandible and collapsible chamber 152 to the scale lever 113, but at a smaller leverage than exists for the anvil member 117, whereby movements of the anvil member 117 in the manner hereinabove described are in part compensated by the counterpoise action of the chamber 152 to control accurately and certainly the movement of the anvil member 117 with respect to its opposed orifice and therefore

the development of variable back pressures in the chamber 128. This counterpoise mechanism, which is adjustable to vary the ratio of the lever arms about axis 114 of member 153 and anvil member 117 enables close adjustment of the sensitivity of response due to back pressure developed in chamber 128.

The other back pressure line 145 leading from the chamber 128 extends to two pressure responsive devices for actuating switches as next to be described. Referring first to Fig. 7 which shows one of the two pressure actuated switch devices, the back pressure line 145 is attached in any suitable way to a connector 155 threadedly received in a hollow stud 156 suitably mounted on a cup-shaped housing 157, said connector having a passage 158 therethrough leading to the chamber 159 interiorly of said housing. Mounted in said chamber 159 and hermetically sealed at its relatively stationary end to the end of said housing is an expansible and collapsible corrugated tubular member or bellows 160 having a movable end wall 161 to which is attached in any suitable way a post 162 leading to the exterior of the housing 157. Variations in back pressure transmitted through the line 145 to the chamber 159 will therefore cause said chamber to vary in volume, increases of pressure causing relative collapse of the bellows 160 and movement of the post 162 to the right as viewed in Fig. 7.

Housing 157 is secured in any suitable way, as by screws 163 to a bracket 164, and pivotally mounted on said bracket at 165, preferably by means of an antifriction bearing, is a lever 166 in the path of movement of the post 162. Cooperating with lever 166 is the actuating member 167 of a supersensitive switch 168 whose details are not here illustrated as they constitute no part of the present invention, various forms of such supersensitive switches being readily available on the market. An increase of back pressure in the chamber 159 will therefore move the post 162 to the right as viewed in Fig. 7, causing the lever 166 to move around its axis 165 and press actuator 167 inwardly to close the switch 168. Associated with the switch 168 is a manually operable adjusting member 169 having a knob 195 whereby the switch may be predeterminedly set to close only upon a given movement of the post 162 and therefore a predetermined increase in the back pressure in chamber 159, or only when the pressure in the chamber 159 is capable of overcoming a predetermined resistance to movement at the switch as fixed by the adjustment of member 169. As before noted, the back pressure line 145 communicates with two such pressure chambers 158 associated with two supersensitive switches 168, and as will be clear from the ensuing description said two switches may be so adjusted that upon existence of a predetermined pressure in one chamber 159 its corresponding switch is actuated but the pressure in the other chamber 159 is insufficient to actuate its associated switch, whereas if the back pressure transmitted by the line 145 is predeterminedly larger, not only is the first referred to chamber 159 effective to actuate its switch 168, but the greater pressure in the other chamber 159 effects the actuation of its associated switch 168 for a purpose to be explained.

Associated with each of the supersensitive switches referred to is a solenoid device one of which is more particularly shown in Fig. 7a. As here shown, a solenoid 170 of any suitable form and construction is suitably mounted on a brack-

et 171 beneath an aperture 172 in the upper member 31 of the housing 13. Pivotally mounted at 173 on a bracket 174 is a bell crank lever having one of its arms 175 disposed in cooperative relationship with the armature or plunger 176 of the solenoid. The opposite arm 177 of the bell crank lever is adapted to actuate an index pin as hereinafter explained. Current from any suitable source, as by use of a detachable plug 180, is led, as by lead 181, to a terminal of each switch 168, the other lead 182 from each switch leading to a terminal 183 of the corresponding solenoid. The other terminal of the solenoid is connected through lead 184 to a synchronizing switch 185 having an operating plunger 186 which is spring pressed outwardly so as to cooperate with a cam surface 187 provided in any suitable way on the arbor 42. The other lead 188 from the synchronizing switch 185 is connected to the return lead 189 of the plug 180. When the arbor 42 is in its lower position as shown in Fig. 11 synchronizing switch 185 is held open, but when arbor 42 is raised to lift the weighing disk 35 as shown in Fig. 12 the cam surface 187 on the arbor effects the closure of the synchronizing switch 185 so as to close the circuit through the switches 168 and the solenoids 170. In order that only one synchronizing switch need be used for the two switches and two solenoids, one lead from the synchronizing switch is common to the two circuits connecting the switches and solenoids.

In order that a signal may appear when the circuit is closed through a switch and its solenoid, leads 190 and 191 are connected in series with leads 188 and 189, one for each circuit through switch and solenoid, and run to suitable signal lamp sockets 192 whose bulbs 193 may be disposed as a part of a control unit hereinafter described, in association with windows 194 on the panel of said unit adjacent the respective adjusting members 195, so that a visual indication may be given when the circuit through each switch and its associated solenoid is closed, these signal lamps being individual to the two switch and solenoid circuits so that the operator by visual observation may know when the pressure in the respective chambers 159 is such as to effect the actuation of the respective switches and thereby close the circuit through the corresponding solenoids.

Associated with each of the weighing disks 35 and mounted on a suitable bracket 199 depending from the table 10 is a pair of axially slideable index pins 196 and 197. When each weighing disk reaches the weighing station the index pins 196 and 197 are aligned with the bell crank arms 177 of the two bell crank levers whose other arms 175 are associated with the armatures or plungers 176 of the solenoids 170, as shown more particularly in Fig. 13. If the back pressure in the chambers 159 is insufficient to actuate either of the switches 168, neither solenoid 170 is actuated, and therefore neither stop pin 196, 197 is moved. If the back pressure in the chambers 159 is sufficient to actuate one of the switches but not both of them, one of the solenoids 170 is actuated to thrust its associated stop pin 196 radially outwardly for a purpose to be explained. If the back pressure in chambers 159 is sufficient to actuate both switches, both solenoids are actuated to thrust both stop pins 196 and 197 outwardly for the purpose to be explained.

A bellows having been weighed at the weighing station and having effected the setting of the index pins 196 and 197, and the arbor 42 there-

after having been lowered to restore the weighing disk 35 to its position on the table 10, the Geneva driving mechanism operates to advance the table 10 by that fraction of a revolution corresponding to the number of disks 35, to move the disk carrying the bellows which has just been weighed to its next or sorting station. As the table 10 moves into the sorting station the setting of the index pins determines the position of automatic stop mechanism now to be described.

Projecting through a slot 200 in the top member 31 of the housing 13 is a lever 202 whose upper end 201 is in the path of the pins 196 and 197 if they have been thrust forwardly by the bell crank arms 177, but which is so located that the ends of the pins 196 and 197 may pass thereby without actuating said lever if neither of the pins has been thrust forwardly by the bell crank arms 177. Lever 202 is pivotally mounted on the frame at 203 in any suitable way—see Fig. 6 wherein said lever is viewed in the opposite direction from that in which it is seen in Fig. 13 and wherein the lever is illustrated diagrammatically. Referring to Fig. 3, the inner end 204 of said lever 202 has pivotally attached thereto at 205 a link 206 whose opposite end is pivotally attached at 207 to a second lever 208 pivotally mounted on the frame of the machine at 209. The opposite end of lever 208 is pivotally attached at 210 to a link 211 whose opposite end is pivotally attached at 212 to a lever 213 pivotally mounted on the cover of the stop mechanism at 214. Referring to Figs. 3 and 4, the opposite end 215 of lever 213 is pivotally connected at 216 to a sliding stop member 217 which may move rectilinearly in a slot 218 provided between ways 219. Sliding member 217 has its inner end beveled as shown at 220, and the extremity 221 of member 217 is normally held against a fixed stop piece 222 by a tension spring 223 secured to lever 213 at 224 and having its opposite end secured at 225 to the cover of the stop mechanism. Interposed between the fixed stop member 222 and a parallel guide member 234 are a pair of movable stop members 226 and 227 which are normally urged toward the left, as viewed in Fig. 4, by coil springs 228 and 229, respectively, that react between said stop members and a fixed part 230 of the stop mechanism.

Spring 223 normally holds the lever 213 in the position shown in full lines in Fig. 4, and through the intermediate links and levers above described the lever 202 is held in its full line position shown in Fig. 6. If neither of the index pins 196 and 197 is thrust forwardly by the bell crank arms 177 the outer ends of said index pins may pass the upwardly projecting end 201 of lever 202 without actuating the same. This is the position of the parts which corresponds with a bellows which is underweight, i. e., one whose resistance to compression is insufficient to actuate either of the switches 168 with their associated solenoids 170 as above referred to.

Assuming that the table 10 is rotating in the direction of the arrow 231 in Fig. 13, it will be perceived that if the back pressure acting in the chambers 159 is sufficient to actuate one of the switches 168 but not the other, this means that the weight of the bellows being measured is between the prescribed upper and lower limits, i. e., it is an acceptable bellows to meet the specifications in question. Under these circumstances the solenoid 170 associated with the index pin 196 actuates said index pin, thrusting the same through

its aperture in the bracket 199, but the solenoid associated with index pin 197 is not energized and pin 197 is left in its relatively withdrawn position. As index pin 196 is now extended outwardly through the bracket 199 it will engage the upwardly projecting end 201 of lever 202 near the end of the movement of the table 10 which brings the weighed bellows into the sorting station, moving lever 202 to the intermediate position 232 shown in Fig. 6 whereby the lever 213, against the tension of the spring 223, moves the sliding stop member 217 upwardly to its intermediate position as viewed in Fig. 4, and as the end of sliding member 217 now frees the end of movable stop member 226, the latter is moved to the left by its spring 228, as viewed in Fig. 4, so that the end 221 of sliding member 217 is held by spring 223 against the stop member 226. If the bellows which was measured is overweight the back pressure developed in the two chambers 159 will be sufficient to actuate both switches 168 and therefore both solenoids 170 whereby both pins 196 and 197 are thrust forwardly to their projecting position. Now as the table 10 moves the measured bellows into the sorting station pin 197 will engage the upwardly projecting end 201 of lever 202 and throw the latter to its extreme position 233 as viewed in Fig. 6, and consequently said lever 202, through the connecting levers and linkage, moves lever 213 against the tension of spring 223 to adjust the sliding member 217 to its uppermost position as shown in Fig. 4. As sliding member 217 now frees the ends of both stop members 226 and 227, both of said stop members are moved to the left as viewed in Fig. 4 by their springs 228 and 229 whereby sliding member 217 is held by spring 223 against the stop member 227. The stop members 226 or 226 and 227 are held in displaced position to control the extent to which the sorting arm can be moved, as hereinafter explained, as long as table 10 is held in its indexed position, but when on the next indexing movement of the table 10 the indexing pins move past the projecting end 201 of lever 202, spring 223 is free to restore the sliding member 217 to its lowermost position as shown in Fig. 4, and the beveled face 220 on the end of said member 217 will, as a result of this movement, cam the stop members 226 and 227 back to their relative positions as shown in Fig. 4, whereby the stop mechanism is reconditioned for actuation by the index pins associated with the next weighing disk 35 when it moves into the sorting station. The index pins 196 and 197 are restored to their innermost position ready for reactivation by the bell crank arms 177 by means of a cam 235 mounted in any suitable way on an arcuate member 236 which surrounds a portion of the periphery of the table 10.

When a weighing disk 35 moves into the sorting station the bellows thereon is operatively associated with a sorting arm whose function is to pick up the bellows on said disk and move it laterally into cooperative relationship with one of a plurality of conveyors depending upon whether the bellows as weighed has been found to be acceptable or overweight or underweight. Referring now to Figs. 3 and 5, the sorting arm comprises a radially extending arm 240 secured in any suitable way to the upper end of a rotatably and slidably mounted tubular post 241 which is guided in its movements by a collar 242, which may be carried by the top member 31 of the housing 13, and by an aperture in a bracket member 243 projecting from the framework. The lower end of

said tubular post is closed by a tubular nut 244 which also constitutes a stop member as will hereafter appear. Slidably mounted in the interior of said tubular post 241 is a plunger-like member 245 having an exteriorly projecting pin 246 which extends through an aperture 247 in nut 244, pin 246 being of smaller diameter than plunger 245 so as to provide a stop shoulder at 248. Also slidably mounted interiorly of said tubular post 241 is a second plunger or collar 249 between which and the plunger 245 is interposed a coil spring 250. A rod 251 projecting upwardly from collar or plunger 249 is pivotally connected at 252 to a bell crank lever 253 disposed in a slot in said post and pivoted at 254 on a bracket 255 projecting downwardly from the arm 240. The opposite arm 256 of said bell crank lever is pivotally connected at 257 to a rod 258 mounted for slidable movement lengthwise of the arm 240 in an apertured bracket 259. Interposed between said bracket and a collar 260 on the rod 258 is a coil spring 261 which normally urges the rod and the parts connected therewith toward the left as viewed in Fig. 5.

The opposite or inwardly disposed end of rod 258 is pivotally connected at 263 (see Fig. 16) to a pair of links 264 and 265 which in turn are pivotally connected at 266 and 267 to a pair of gripping levers 268 and 269 that are pivotally mounted on the end of the arm 240 at 270 and 271. Slidably and adjustably mounted on each of said gripping levers is a gripping member 272, said latter members being slidable along the levers 268 and 269, but suitably held fixedly in adjusted position as by thumb screws 273, so that said members may be variously spaced for cooperation with bellows of different diameters. As shown, each of said gripping members is provided with a reentrant portion 274 providing a socket which is preferably lined with some soft material such as felt 275, so that when the gripping members are brought into their gripping position as shown in dotted lines in Fig. 16, although they will firmly grip a bellows on a weighing disk 35 at the sorting station, there will be no danger of the thin delicate walls of the bellows being injured by the gripping contact of said members therewith.

Referring to Fig. 3, the outwardly projecting pin 246 is associated with the end 277 of a crank arm 278 mounted on a rod 279 rotatably supported in brackets 280. The opposite end of rod 279 has a crank arm 281 extending therefrom and provided with a cam follower 282 which cooperates with a cam disk 283 mounted on the shaft 47 hereinbefore referred to, said cam disk 283 having suitable dwells to effect the movements next to be described.

When a bellows reaches the sorting station, cam 283 depresses crank arm 281 to elevate crank arm 278, thereby thrusting pin 246 inwardly until the end 277 of arm 278 engages the outer face of the tubular stop nut 244. During this movement plunger 245 is raised as viewed in Fig. 5, compressing spring 250 and thereafter, through plunger or collar 249, rod 251 and bell crank 253, moving rod 258 to the right, as viewed in Fig. 3, to spread the links 264 and 265 and cause the gripping levers 268, 269 to pivot around their axes 270 and 271, bringing the gripping members 272 into the dotted line position shown in Fig. 16 whereby the bellows in the sorting station is firmly gripped. Further movement of end 277 of crank arm 278 in an upward direction as viewed in Fig. 3 causes the tubular post 241

to slide upwardly through guides 242 and 243, lifting the arm 240 so as to elevate the bellows 39 out of contact with the disk 35 and its grooves. The tubular post 241 then being rotated by mechanism next to be described, the bellows is moved to its proper position where the sorting arm 240 with its gripping members 272 are lowered and opened to deposit the bellows by the reverse operation of the trains just described, after which the hollow post 241 is rotated back to its initial position for cooperation with the next bellows to be moved into the sorting station.

Fixedly mounted on the exterior of the tubular post 241 is a collar 285 provided with a slotted arm 286. Reacting between said collar 285 and the underside of the collar 242 is a coil spring 287 disposed exteriorly of and around the hollow post 241, said spring normally urging the tubular post downwardly to retain contact with the crank arm 277 until the post is returned to its lower position where it is stopped by engagement of arms 286 with the parts next to be described. Referring to Fig. 3, the slot 288 in said arm 286 receives an upwardly projecting pin 289 carried by a slidable member or block 290 guided in its rectilinear movements in any suitable way as by ways 291 provided by the framework. Also slidably mounted in said ways 291 is a second block 292 which may slide with respect to the block 290 on a pin 293 surrounding which is a coil spring 294 that reacts between the blocks 290 and 292. Thereby the movement of the block 292 is transmitted through the spring to the block 290 but said spring can be compressed to permit movement of the block 292 with respect to the block 290 when the latter block is stopped as herein-after explained. The opposite end of block 292 is provided with a cam follower 295 which cooperates with a cam 296 here shown as mounted on the stub shaft 20 of the Geneva disk 18, cam follower 295 being urged toward cam 296 by a spring 298 reacting between a pin 299 on block 292 and a pin 239 on a stationary part of the framework. The underside of block 290 is provided with a lug 297 adapted to engage the fixed stop 222 or the stop members 226 or 227 is thrust to the left as viewed in Fig. 4 as hereinabove explained.

When the cam actuated mechanism heretofore described has been operated to grip a bellows at the sorting station and lift the same free of its weighing disk 35, cam 296 operates cam follower 295 to move block 292 in an outward direction as viewed in Fig. 3. Block 292 through spring 294 moves block 290 with its depending lug 297 until the latter engages one of the stops 222, 226 or 227, after which if the cam follower continues to press block 292 outwardly, the spring 294 can be compressed without injury to the parts. The described movement of block 290 through pin 299, due to its coaction with the slot 288 in arm 286, causes the collar 285 and the hollow post 241 to rotate around the axis of the hollow post 241, the extent of said rotation being predetermined by the engagement of lug 297 with one or another of the stops 222, 226 or 227. After the bellows is deposited, continued rotation of the cam 296 causes reverse rotation of the arm 240 and hollow post 241 to restore the arm to its original position.

Disposed beside the table 19 and underlying the path of movement of the gripping elements on the sorting arm 240 are three endless conveyors 303, 304 and 305 (see Figs. 13 and 15). Said conveyors may be driven in any suitable way as by sprocket and chain mechanism from the

driving mechanism of the machine, the driving sprocket thereof being diagrammatically indicated in Fig. 3 at 306. Conveyor 303 is so disposed that if both stop members 226 and 227 are in operative position the sorting arm is stopped over conveyor 303 so as to receive a bellows when deposited by said arm. Conveyor 304 is so disposed that if stop member 226 is in operative position said sorting arm 240 is stopped over said conveyor to receive a bellows when deposited therefrom. Conveyor 305 is so disposed that when neither stop members 226 nor 227 is in position, so that the lug 297 may move until it engages the fixed stop 222, said conveyor is in position to receive a bellows when deposited by said arm 240. Thereby, depending upon whether the bellows as measured has been found to be overweight, acceptable or underweight, it is deposited on one of the three conveyors.

Said conveyors are driven continuously to move the bellows deposited thereon out of the machine into accumulators 307, 308 and 309 respectively (see Fig. 2), said accumulators preferably being downwardly inclined in an outward direction so that the bellows delivered thereto from the conveyors 303, 304 and 305 will be easily displaced downwardly and outwardly for ready removal. The conveyors are preferably disposed in the horizontal plane of the table so that a downward movement of the gripping mechanism will deposit the bellows on the conveyors by the same amount of movement as occurs in the upward movement of said gripping mechanism in lifting the bellows off of the weighing disks 35.

The admission of pressure fluid as compressed air to the cylinder 83 of the weighing head is preferably controlled automatically so as to occur only after the bellows 39 has elevated the spindle 71 from the position shown in Fig. 11 to the position shown in Fig. 12. Such automatic control of the admission of compressed air may be effected in any suitable way. As shown diagrammatically in Fig. 3, the shaft 47 also carries a cam 311 cooperatively associated with the operating member 312 of a three-way valve so that at proper times in the cycle of operation of the machine cam 311 will operate valve 312 to admit compressed air to the cylinder 83 of the weighing head, or exhaust the same to atmosphere. When pressure is released in cylinder 83 plunger 78 is raised as viewed in Fig. 11 by the tension of spring 82, lifting the collet member 68 to free the gripping elements 70 so that head 74 may follow the bellows 39 downwardly as disk 35 is lowered until the collar 72 on spindle 71 engages the end of the gripping elements 70 and holds the head 74 in its suspended position as shown in Fig. 11.

The switches 168 with their associated adjusting and visible indicating elements are preferably disposed in a separate control box as shown in Fig. 1 wherein the control box 315 has mounted on its panel the adjusting elements 195 of the two switches and, in association with each, the corresponding visual indicating element at 194. Said control box may also be provided with any other suitable indicating means as shown at 316, and pressure gauges may be disposed on the top member 31 of the housing 13, as shown at 318 and 319, for the purpose of indicating visually the pressure of the fluid at desired points in the system. Suitable pressure regulators, surge tanks, etc., may be associated with each or both of fluid pressure lines leading to the cylinder 83 and the chamber 129 so that substantially constant pres-

sure of predetermined value may be delivered thereto.

As the operation of the several component parts of the machine has been described in connection with the construction thereof, it will be sufficient to summarize the operation. The operator stands at the front of the machine and merely places a bellows on each weighing disk 35, centrally disposed with respect to the axis thereof, as said disks pass through their inactive positions. Assuming that the circuit through the motor 29 is closed by operating the switch 30, the motor 29, through the belt 28 and pulley 26, drives the speed reducing mechanism 25 from which the shafts 24 and 58 are driven whereby, through the beveled gearing 22, 23 and 48, 49, the stub shafts 20 and 47 are rotated to drive the Geneva mechanism 16, 17, 18, 19 and the several cams hereinbefore described. Said Geneva mechanism operates intermittently and at predetermined times to move the table 10 through a fraction of a rotation, and thereupon to lock said table against rotational displacement, the extent of movement depending upon the number of weighing disks employed. Thus where as illustrated six weighing disks 35 are used, each indexing movement of the table 10 is one of 60 degrees rotation.

When each disk 35 is moved into that station which has been denominated the weighing station, cam 46 on shaft 47 effects the elevation of the arbor 42 to engage and pick up the weighing disk 35 which has reached that station. Elevation of disk 35 carries upwardly the bellows 39 thereon picking up the head 74 and sliding the spindle 71 inwardly with respect to the collet mechanism to the extent required by the free length of the bellows being measured. Thereupon cam 311 operates the three-way valve 312 to admit compressed air to the cylinder 83 of the weighing head, causing plunger 78 to move downwardly to first cause tubular member 68 to grip the elements 70 and lock the same to the spindle 71, after which transverse member 59 is moved downwardly by the plunger 78, against the tension of the springs 61, until stop member 90 engages end member 58, the magnitude of this latter movement, determined by the spacing of stop member 90 from end member 58, exactly determining the weighing stroke or load.

The resistance of the bellows 39 to compression during this weighing stroke is reflected in the movement of the scale lever 109 about its axis 107, said movement being transmitted through the link 111 to the scale lever 113 whereby the movement is magnified. Movement of scale lever 113 advances the anvil member 117 toward the aperture 141 by an amount which is exactly proportional to the resistance to compression of the bellows 39. Thereby a back pressure is established in the chamber 128 which, on the one hand, is transmitted to the expandable and collapsible chamber 152 to act as a counterpoise, while, on the other hand, said back pressure is transmitted through the back pressure line 145 to the chambers 159. If the bellows is underweight the magnitude of the back pressure in chambers 159 is insufficient to operate either of the switches 168, and therefore the associated solenoids 170, which are placed in circuit by the synchronizing switch 185 as the arbor 42 is elevated, do not move the index pins 196 and 197. If the weight of the bellows falls between the upper and lower permissible limits the back pressure in one of the chambers 159 is sufficient to close its associated switch 168 and energize

the corresponding solenoid which will thrust outwardly the index pin 196, the other switch and solenoid remaining inactive. If the bellows is overweight, the back pressure in the chambers 159 is sufficient to actuate both switches 168 so that both solenoids are energized to thrust outwardly both stop pins 196 and 197.

The timing of the mechanism is such as to assure that the complete weighing operation is effected while the bellows is at the weighing station and, furthermore, to assure sufficient time to provide for the return of the weighing disk to the turntable 10, the cam 46 effecting the lowering of the arbor 42, which opens the synchronizing switch 185, and the cam 311 operating the three-way valve 312 to exhaust the cylinder 83, which opens the collet mechanism and permits the head 74 to return to its original position. The weighing cycle having thus been completed with the parts restored to original position, but with the index pins 196 and 197 properly positioned with respect to the weight of the bellows which was measured, the table 10 is indexed by its Geneva mechanism to advance the measured bellows to the sorting station at which station it is operatively disposed with respect to the gripping members 272.

As the bellows so moves into the sorting station the index pins 196, 197, by failing to actuate the lever 202 or by moving the same to one or the other of its two positions of displacement, effects through the connecting levers and linkage a movement of the slideable member 217 which predetermines which of the stops 222, 226 and 227 shall be effective to determine the extent of movement of the sorting arm 240. When the bellows reaches the sorting station, cam 283 actuates crank arm 281 to move crank arm 278 upwardly to first actuate the bell crank lever 253, 256 and thrust rod 258 in such a direction as to move the gripping levers 268 and 269 around their pivots and bring their gripping members into firm contact with the bellows. Further movement of the crank arm 278 causes the hollow post 241 to slide upwardly whereby the arm 240 lifts the bellows out of engagement with the weighing disk 35. Cam 296 now actuates block 292, and the latter through spring 294 actuates block 290, sliding the same until the depending lug 297 engages that one of the stops 222, 226, 227 that has been made effective by the index pins. During this movement the block 290 through its pin 289 and the slotted arm 286 rotates the hollow post 241 to that position determined by the aforesaid stops wherein the bellows is immediately over the particular conveyor which is determined by stop mechanism. The cam operated mechanisms just referred to then operate reversely to effect the deposit of the bellows on the underlying conveyor, after which the post 241 is rotated in a direction to return the clamping members to their proper position for cooperation with the next bellows moved into the sorting station.

The machine can be readily set for handling a wide variety of lengths and sizes of bellows as well as for closely predetermining various upper and lower limits for acceptable bellows. By rotating the screw 121 the tubular member 93 may be moved upwardly and downwardly on the column 99 so as to dispose the head 74 at varying distances above the table 10 from co-operating with bellows of different lengths. However, once the machine is thus set to handle a particular length of bellows the weighing goes

forward without respect to the usual tolerant variations in the length of the bellows, because the head 74 can move the spindle 71 inwardly with respect to the collet mechanism to varying extents before the weighing action is initiated, so that no variable is introduced because of different free lengths of the bellows being weighed.

By providing suitable grooves on the weighing disks 35 bellows of varying diameters may be readily centered with respect thereto, and by adjusting the clamping members 272 on the clamping levers 268, 269, so as to space them at variable distances, the latter can be brought into firm engagement with bellows of a wide variety of diameters without danger of gripping them so tightly as to injure the relatively thin metal of which the walls are conventionally composed.

By placing weights on the scale pan 119 respectively corresponding with the upper and lower acceptable limits of the bellows to be weighed the switches 168 can be exactly adjusted by their adjusting members 195 so as to be responsive to the back pressures thereby produced in the chambers 159, the closure of the switches being disclosed by the visually indicating devices 194, and by using different weights on the scale pan the machine may therefore be accurately adjusted in conformity with different upper and lower limits as required by different specifications, different sizes of bellows, etc.

At the same time, by properly proportioning the ratio of the lever arms of the anvil member 117 and the operating point of contact of counterpoise bellows 152 with respect to the axis 114 of lever 113 the counterpoise action of bellows 152 may be nicely adjusted so as to exactly predetermine the sensitivity of response of the weighing mechanism to the resistance to compression of the bellows being weighed. Furthermore, by accurately adjusting the counterweights 101, 102 the weighing head, together with its associated scale levers, can be exactly counterbalanced so that the response of the weighing head is an exact and accurate reflection of the resistance to compression of the bellows being weighed.

It will therefore be perceived that by the present invention a sorting mechanism has been provided which entirely eliminates the human factor of error in separating acceptable elements, having a predetermined range of elastic resistance to compression, from elements whose resistance is above or below the specified limits, and at the same time the tediousness and inefficiency of earlier procedures for sorting such elements have been entirely overcome. As the sorting is entirely independent of the capacity of the workman to correctly measure loads, deflections, and the like, the machine can be run by relatively unskilled workmen with assurance that the elements will be properly sorted into their respective classes, the operator of the machine being required merely to place the elements in succession on the weighing disks with no greater responsibility than to see that they are properly centered. At

the same time the machine is composed of parts which are inexpensive to manufacture, assemble, service and operate so that elements may be sorted much more rapidly and efficiently, and therefore at smaller cost, than has heretofore been the case.

While the embodiment of the invention illustrated on the drawings has been described with considerable particularity it is to be expressly understood that the invention is not restricted thereto, as the invention is capable of receiving a

variety of mechanical expressions, as will now be apparent to those skilled in the art, while changes may be made in the details of construction and arrangement of the component parts without departing from the spirit of the invention. While the invention has been exemplified by reference to its use as a means for sorting bellows, it will now be apparent to those skilled in the art that the invention is not limited to this use, as it may be readily adapted to the accurate sorting of a wide variety of elements whose characteristics may be classified according to varying capacity to resist compression. While particular devices have been disclosed for indexing the table, controlling the admission and exhaust of fluid pressure, cam-actuating the several mechanisms, driving the machine, etc., it will be understood that the invention is not to be limited to such devices as other suitable devices may be employed to perform corresponding functions without departing from the broader aspects of the present invention. Reference is therefore to be had to the appended claims for a definition of the invention.

What is claimed is:

1. In a machine for sorting elements according to different resistances to compression, in combination with a plurality of conveyors for feeding sorted elements out of the machine, indexing means for intermittently advancing elements to be sorted into a weighing station and thereafter to a sorting station, element-transporting means at the sorting station for removing elements therefrom, stop mechanism associated with said last named means for predetermining into alignment with which conveyor said transporting means shall move, a fluid pressure device at said weighing station for applying a predetermined compression stroke to an element at said station, and fluid pressure means responsive to variations in the resistance to compression of elements at the weighing station for predeterminately setting said stop mechanism.

2. In a machine for sorting elements according to different resistances to compression, in combination with a plurality of conveyors for feeding sorted elements out of the machine, indexing means for intermittently advancing elements to be sorted into a weighing station and thereafter to a sorting station, element-transporting means at the sorting station for removing elements therefrom, stop mechanism associated with said last named means for predetermining into alignment with which conveyor said transporting means shall move, a fluid pressure device at said weighing station for applying a predetermined compression stroke to an element at said station, means at said weighing station variably responsive to variable degrees of compression of said elements, and fluid pressure means for actuating said stop mechanism actuated by variable degrees of movement of said last named means in response to the varying resistances to compression of said elements.

3. In a machine for sorting elements according to different resistances to compression, in combination with a plurality of conveyors for feeding sorted elements out of the machine, indexing means for intermittently advancing elements to be sorted into a weighing station and thereafter to a sorting station, element-transporting means at the sorting station for removing elements therefrom, stop mechanism associated with said last named means for predetermining into alignment with which conveyor said transporting means shall move, a fluid pressure

device at said weighing station for applying a predetermined compression stroke to an element at said station, means operatively associated with said pressure device and variably responsive to different degrees of compression of said elements, fluid pressure means actuated by said last named means for developing variable pressures therein, and means operated by said variable pressures for predeterminately setting said stop mechanism.

4. In a machine for sorting elements according to different resistances to compression, in combination with a plurality of conveyors for feeding sorted elements out of the machine, indexing means for intermittently advancing elements to be sorted into a weighing station and thereafter to a sorting station, element-transporting means at the sorting station for removing elements therefrom, stop mechanism associated with said last named means for predetermining into alignment with which conveyor said transporting means shall move, a fluid pressure device at said weighing station for applying a predetermined compression stroke to an element at said station, means associated with said fluid pressure device and variably responsive to different degrees of resistance to compression of the elements at said station, fluid pressure means actuated by said last named means for developing predetermined pressures proportional to the resistance to compression of the elements being measured, and means actuated by said last named fluid pressure means for predeterminately setting said stop mechanism.

5. In a machine for sorting elements according to different resistances to compression, in combination with a plurality of conveyors for feeding sorted elements out of the machine, indexing means for intermittently advancing elements to be sorted into a weighing station and thereafter to a sorting station, element-transporting means at the sorting station for removing elements therefrom, stop mechanism associated with said last named means for predetermining into alignment with which conveyor said transporting means shall move, a fluid pressure device at said weighing station for applying a predetermined compression stroke to an element at said station, means associated with said fluid pressure device and movable responsively to the resistance to compression of each element at said station, a fluid pressure device associated with said resistance-responsive means, means operable by said resistance-responsive means for varying the pressure in said last named fluid pressure device, and means operable by variations in pressure in said last named device for predeterminately setting said stop mechanism.

6. In a machine for sorting elements according to different resistances to compression, in combination with a plurality of conveyors for feeding sorted elements out of the machine, indexing means for intermittently advancing elements to be sorted into a weighing station and thereafter to a sorting station, element-transporting means at the sorting station for removing elements therefrom, stop mechanism associated with said last named means for predetermining into alignment with which conveyor said transporting means shall move, a pressure responsive device at said weighing station for applying a predetermined compression stroke to an element at said station, means associated with said pressure responsive device and movable responsively to the resistance to compression of each ele-

21

ment at said station, a fluid pressure device associated with said compression-responsive means, said last named device including an orifice through which a flow of fluid is maintained and said compression-responsive means including an element actuated thereby and cooperating with said orifice for variably developing back pressure in said last named fluid pressure device, and means selectively operated by variations in said back pressure for predeterminately setting said stop mechanism.

7. In a machine for sorting elements according to different resistances to compression, in combination with a plurality of conveyors for feeding sorted elements out of the machine, indexing means for intermittently advancing elements to be sorted into a weighing station and thereafter to a sorting station, element-transporting means at the sorting station for removing elements therefrom, stop mechanism associated with said last named means for predetermining into alignment with which conveyor said transporting means shall move, a fluid pressure device at said weighing station for applying a predetermined compression stroke to an element at said station, means associated with said fluid pressure device and movable responsively to the resistance to compression of each element at said station, a fluid pressure device associated with said compression-responsive means, said last named means including an orifice through which a flow of fluid is maintained and said compression-responsive means including a member actuated thereby for movement toward and away from said orifice to vary the flow of fluid therethrough and thereby develop variable back pressures in said last named fluid pressure device, and means selectively operated by the variable back pressures in said last named fluid pressure device for predeterminately setting said stop mechanism.

8. In a machine for sorting elements according to different resistances to compression, in combination with a plurality of conveyors for feeding sorted elements out of the machine, indexing means for intermittently advancing elements to be sorted into a weighing station and thereafter to a sorting station, element-transporting means at the sorting station for removing elements therefrom, stop mechanism associated with said last named means for predetermining into alignment with which conveyor said transporting means shall move, a fluid pressure device at said weighing station for applying a predetermined compression stroke to an element at said station, means associated with said fluid pressure device and movable responsively to the resistance to compression of each element at said station, a fluid pressure device associated with said compression-responsive means, said last named means including an orifice through which a flow of fluid is maintained and said compression-responsive means including a member actuated thereby for movement toward and away from said orifice to vary the flow of fluid therethrough and thereby develop variable back pressures in said last named fluid pressure device, a plurality of expandable and collapsible chambers in communication with said last named fluid pressure device, means associated with each element and selectively actuated by said chambers under the variations of back pressure therein, and means at said sorting station operated by said last named means for predeterminately setting said stop mechanism.

9. In a machine for sorting elements accord-

22

ing to different resistances to compression, in combination with a plurality of conveyors for feeding sorted elements out of the machine, indexing means for intermittently advancing elements to be sorted into a weighing station and thereafter to a sorting station, element-transporting means at the sorting station for removing elements therefrom, stop mechanism associated with said last named means for predetermining into alignment with which conveyor said transporting means shall move, a fluid pressure device at said weighing station for applying a predetermined compression stroke to an element at said station, means associated with said fluid pressure device and movable responsively to the resistance to compression of each element at said station, a fluid pressure device associated with said compression-responsive means, said last named means including an orifice through which a flow of fluid is maintained and said compression-responsive means including a member actuated thereby for movement toward and away from said orifice to vary the flow of fluid therethrough and thereby develop variable back pressures in said last named fluid pressure device, a plurality of expandable and collapsible chambers in communication with said last named fluid pressure device, a switch associated with each chamber and selectively closed thereby when a predetermined back pressure has been developed in said chamber, a plurality of members associated with each element being measured, electrical means operated by said switches for selectively moving said members into operative position, and means at said sorting station operable by said members for predeterminately setting said stop mechanism.

10. In a machine for sorting elements according to different resistances to compression, in combination with a plurality of conveyors for feeding sorted elements out of the machine, indexing means for intermittently advancing elements to be sorted into a weighing station and thereafter to a sorting station, element-transporting means at the sorting station for removing elements therefrom, stop mechanism associated with said last named means for predetermining into alignment with which conveyor said transporting means shall move, a fluid pressure device at said weighing station for applying a predetermined compression stroke to an element at said station, fluid pressure means associated with said first named fluid pressure device and responsive to variations in the resistance to compression of each element at said weighing station, means actuated by variations of pressure in said second named fluid pressure device for predeterminately setting said stop mechanism, and means at the weighing station and operable when each element arrives thereat for bringing said first named fluid pressure device and said element into cooperative relationship.

11. In a machine for sorting elements according to different resistances to compression, in combination with a plurality of conveyors for feeding sorted elements out of the machine, indexing means for intermittently advancing elements to be sorted into a weighing station and thereafter to a sorting station, element-transporting means at the sorting station for removing elements therefrom, stop mechanism associated with said last named means for predetermining into alignment with which conveyor said transporting means shall move, a fluid pressure device at said weighing station for applying a

predetermined compression stroke to an element at said station, fluid pressure means associated with said first named fluid pressure device and responsive to variations in the resistance to compression of each element at said weighing station, means actuated by variations of pressure in said second named fluid pressure device for predeterminately setting said stop mechanism, and means at the weighing station and operable when each element arrives thereat for bringing said first named fluid pressure device and said element into cooperative relationship, said last named means including a disk on which each element is supported and means at the weighing station for lifting a disk and its supported element into engagement with said first named fluid pressure device.

12. In a machine for sorting elements according to different resistances to compression, in combination with a plurality of conveyors for feeding sorted elements out of the machine, indexing means for intermittently advancing elements to be sorted into a weighing station and thereafter to a sorting station, element-trans- porting means at the sorting station for removing elements therefrom, stop mechanism associated with said last named means for predetermining into alignment with which conveyor said trans- porting means shall move, a fluid pressure device at said weighing station for applying a pre- determined compression stroke to each element at said station, fluid pressure means associated with said first named fluid pressure device and responsive to variations in the resistance to compression of each element at said weighing station, means actuated by variations of pressure in said second named fluid pressure device for predeterminately setting said stop mechanism, means at the weigh- ing station and operable when each element ar- rives thereat for bringing said first named fluid pressure device and said element into cooperative relationship, said last named means includ- ing a disk on which each element is supported and means at the weighing station for lifting a disk and its supported element into engagement with said first named fluid pressure device, and means synchronized with said lifting means for admitting fluid pressure to said first named fluid pressure device after said element and said fluid pressure device have been brought into coopera- tive relationship.

13. In a machine for sorting elements according to different resistances to compression, in combination with a plurality of conveyors for feeding sorted elements out of the machine, in- dexing means for intermittently advancing ele- ments to be sorted into a weighing station and thereafter to a sorting station, element-trans- porting means at the sorting station for remov- ing elements therefrom, stop mechanism asso- ciated with said last named means for predeter- mining into alignment with which conveyor said trans- porting means shall move, a fluid pres- sure device at said weighing station for applying a predetermined compression stroke to each ele- ment at said station, fluid pressure means asso- ciated with said first named fluid pressure device and responsive to variations in the resistance to compression of each element at said weighing station, means actuated by variations of pressure in said last named fluid pressure device for predeterminately setting said stop mechanism, means at the weighing station and operable when each element arrives thereat for bringing said first named fluid pressure device and said element into

cooperative relationship, said last named means including a disk on which an element is supported and means at the weighing station for lifting a disk and its supported element into engagement with said first named fluid pressure device, and said last named fluid pressure device including means engageable with the element to be measured and variably positioned with respect to said fluid pressure device by variations in the free length of the element to be measured.

14. In a machine for sorting elements accord- ing to different resistances to compression, in combination with a plurality of conveyors for feeding sorted elements out of the machine, in- dexing means for intermittently advancing ele- ments to be sorted into a weighing station and thereafter to a sorting station, element-trans- porting means at the sorting station for remov- ing elements therefrom, stop mechanism asso- ciated with said last named means for predeter- mining into alignment with which conveyor said trans- porting means shall move, a fluid pressure device at said weighing station for applying a predetermined compression stroke to each ele- ment at said station, fluid pressure means asso- ciated with said first named fluid pressure device and responsive to variations in the resistance to compression of each element at said weighing station, means actuated by variations of pres- sure in said last named fluid pressure device for predeterminately setting said stop mechanism, means at the weighing station and operable when each element arrives thereat for bringing said first named fluid pressure device and said ele- ments into cooperative relationship, said last named means including a disk on which each element is supported and means at the weighing station for lifting a disk and its supported ele- ment into engagement with said first named fluid pressure device, and said first named fluid pressure device including a disk engageable with the end of the element and having a stem, a collet mechanism cooperating with said stem for lock- ing said stem and disk in engagement with the element at its free length and means for actu- ating said collet mechanism preliminarily to apply- ing said compression stroke to said element.

15. In a machine for sorting elements accord- ing to different resistances to compression, in combination with a plurality of conveyors for feeding sorted elements out of the machine, in- dexing means for intermittently advancing ele- ments to be sorted into a weighing station and thereafter to a sorting station, element-trans- porting means at the sorting station for remov- ing elements therefrom, stop mechanism asso- ciated with said last named means for predeter- mining into alignment with which conveyor said trans- porting means shall move, a fluid pressure device at said weighing station for applying a pre- determined compression stroke to an element at said station, fluid pressure means associated with said first named fluid pressure device and re- sponsive to variations in the resistance to com- pression of each element being measured, means operated by variations of pressure in said second named fluid pressure means for predeterminately setting said stop mechanism, and counterbalanc- ing means cooperating with said fluid pressure device and said fluid pressure means whereby said fluid pressure means responds only to varia- tions in the resistance to compression of the elements being measured.

16. In a machine for sorting elements accord- ing to different resistances to compression, in

75

combination with a plurality of conveyors for feeding sorted elements out of the machine, indexing means for intermittently advancing elements to be sorted into a weighing station and thereafter to a sorting station, element-trans-
porting means at the sorting station for removing elements therefrom, stop mechanism associated with said last named means for predeter-
mining into alignment with which conveyor said transporting means shall move, a fluid pressure device at said weighing station for applying a predeter-
mined compression stroke to an element at said station, a second fluid pressure means associated with said first named fluid pressure device and responsive to variations in the resist-
ance to compression of each element being measured, means operated by variations of pressure in said second named fluid pressure means for predeterminately setting said stop mechanism, said second named fluid pressure means including lever means upon which said first named fluid pressure device is mounted, an orifice device and a member mounted on said lever means for cooperating with said orifice device to develop back pressure therein, and counter-
balancing means cooperating with said lever means for counterbalancing said lever means and the pressure device and member mounted thereon.

17. In a machine for sorting elements accord-
ing to different resistances to compression, in combination with a plurality of conveyors for feeding sorted elements out of the machine, indexing means for intermittently advancing elements to be sorted into a weighing station and thereafter to a sorting station, element-trans-
porting means at the sorting station for removing elements therefrom, stop mechanism associated with said last named means for predeter-
mining into alignment with which conveyor said transporting means shall move, a fluid pressure device at said weighing station for applying a predeter-
mined compression stroke to an element at said station, a second fluid pressure operated device associated with said first named fluid pres-
sure device and including an orifice through which a flow of fluid is maintained, lever means upon which said first named fluid pressure device is mounted and variably moved by said first named fluid pressure device in conformity with the resistance to compression of the elements being weighed, a member on said lever means movable in response to variations to resistance to compression of the elements being measured to vary the quantity of fluid flowing from said orifice device and thereby the back pressure developed therein, operating members associated with each element being measured, pressure actuated means responsive to the back pressure in said orifice device for setting said operating members, and means at said sorting station actuated by said operating members for predeter-
minately setting said stop mechanism.

18. In a machine for sorting elements accord-
ing to different resistances to compression, in combination with a plurality of conveyors for feeding sorted elements out of the machine, indexing means for intermittently advancing elements to be sorted into a weighing station and thereafter to a sorting station, element-trans-
porting means at the sorting station for removing elements therefrom, stop mechanism associated with said last named means for predeter-
mining into alignment with which conveyor said transporting means shall move, and means re-

sponsive to different degrees of compression of said elements for predeterminately setting said stop mechanism, said transporting means includ-
ing a pivotally and vertically movable arm, ele-
ment gripping means carried by said arm, means for actuating said gripping means to grip an element at the sorting station and thereafter elevate said arm to lift said element from said sorting station and means for thereafter rotating said arm to move said gripping means into alignment with one of said conveyors as pre-
determined by said stop mechanism.

19. In a machine for sorting elements accord-
ing to different resistances to compression, in combination with a plurality of conveyors for feeding sorted elements out of the machine, indexing means for intermittently advancing elements to be sorted into a weighing station and thereafter to a sorting station, element-trans-
porting means at the sorting station for removing elements therefrom, stop mechanism associated with said last named means for predeter-
mining into alignment with which conveyor said transporting means shall move, and means re-
sponsive to different degrees of compression of said elements for predeterminately setting said stop mechanism, said transporting means includ-
ing an arm at said sorting station, gripping means carried by said arm, a tubular post on which said arm is mounted, means mounting said post for pivotal and sliding movement, means in said post for operating said gripping means, means cooperating with said post for first actuating said gripping means and then elevating said post and arm, and means thereafter co-
operating with said post to move the gripping means on said arm into alignment with one of said conveyors as predetermined by said stop mechanism.

20. In a machine for sorting elements accord-
ing to different resistances to compression, in combination with a plurality of conveyors for feeding sorted elements out of the machine, indexing means for intermittently advancing elements to be sorted into a weighing station and thereafter to a sorting station, element-trans-
porting means at the sorting station for removing elements therefrom, stop mechanism associated with said last named means for predeter-
mining into alignment with which conveyor said transporting means shall move, and means re-
sponsive to different degrees of compression of said elements for setting said stop mechanism in conformity with the response of said responsive means, said transporting means including an arm at said sorting station, gripping means carried by said arm, a tubular post on which said arm is mounted, means mounting said post for pivotal and sliding movement, means for operat-
ing said gripping means carried by said arm, means in said post for operating said last named means and including a member projecting ext-
eriorly thereof, means including a member eng-
aging said last named member and operable to actuate the means interiorly of said post and thereby said gripping means and thereafter to move said post vertically to remove an element from said sorting station, and further means cooperating with said post to rotate the same and move said gripping means into alignment with one of said conveyors as predetermined by said stop mechanism.

21. In a machine for sorting elements accord-
ing to different resistances to compression, in combination with a plurality of conveyors for

feeding sorted elements out of the machine, indexing means for intermittently advancing elements to be sorted into a weighing station and thereafter to a sorting station, element-trans- porting means at the sorting station for removing elements therefrom, stop mechanism associated with said last named means for predeter- mining into alignment with which conveyor said transporting means shall move, a fluid pressure device at said weighing station for applying a predetermined compression stroke to an element at said station, a second fluid pressure device associated with said first named fluid pressure device, means responsive to variations in the resistance to compression of elements at the weigh- ing station for varying the back pressure in said last named fluid pressure device, actuating means for the stop mechanism associated with each of the elements being measured, means responsive to variations in pressure in said last named fluid pressure device for predeterminately setting said actuating means, and means at the sorting station operated by said actuating means for pre- determinately setting said stop mechanism.

22. In a machine for sorting elements accord- ing to different resistances to compression, in combination with a plurality of conveyors for feeding sorted elements out of the machine, indexing means for intermittently advancing elements to be sorted into a weighing station and thereafter to a sorting station, element-trans- porting means at the sorting station for removing elements therefrom, stop mechanism associated with said last named means for predeter- mining into alignment with which conveyor said transporting means shall move, a fluid pressure device at said weighing station for applying a predetermined compression stroke to an element at said station, a second fluid pressure device associated with said first named fluid pressure device, means responsive to variations in the resistance to compression of elements at the weigh- ing station for varying the back pressure in said last named fluid pressure device, actuating means for the stop mechanism associated with each of the elements being measured, means responsive to variations in pressure in said last named fluid pressure device for predeterminately setting said actuating means, a member at the sorting station operable by said actuating means to a plurality of positions, and a plurality of stops under the control of said member, said transporting means including a pivotally mounted arm for trans- porting elements to said conveyors and operating means therefor including a member cooperating with said stops to predetermine to which conveyor the element is delivered.

23. In a machine for sorting elements accord- ing to different resistances to compression, in combination with a plurality of conveyors for feeding sorted elements out of the machine, indexing means for intermittently advancing elements to be sorted into a weighing station and thereafter to a sorting station, element-trans- porting means at the sorting station for removing elements therefrom, stop means associated with said last named means for predetermining into alignment with which conveyor said transporting means shall move, a pressure responsive device at said weighing station for applying a predetermined compression stroke to an element at said station, a second fluid pressure device associated with said first named fluid pres- sure device, means responsive to variations in the resistance to compression of elements at the weighing station for varying the pressure in said

last named fluid pressure device, a pair of pres- sure responsive members operable by variations of pressure developed in said last named fluid pressure device, means for setting said pressure responsive members to respond to predetermined upper and lower limits of pressure correspond- ing to the desired upper and lower limits of com- pression desired for said elements, and means actuated by said pressure responsive members for predeterminately setting said stop mech- anism.

24. In a machine for sorting elements accord- ing to different resistances to compression, in combination with a plurality of conveyors for feeding sorted elements out of the machine, indexing means for intermittently advancing elements to be sorted into a weighing station and thereafter to a sorting station, element-trans- porting means at the sorting station for removing elements therefrom, stop mechanism associated with said last named means for predeter- mining into alignment with which conveyor said transporting means shall move, a pressure responsive device for applying a predetermined compression stroke to an element at said weigh- ing station, a second fluid pressure device as- sociated with said first named fluid pressure device, means responsive to variations in the resistance to compression of elements at the 30 weighing station for varying the pressure in said last named fluid pressure device, a pair of pres- sure responsive members operable by variations of pressure developed in said last named fluid pressure device, means for setting said pressure responsive members to respond to predeter- 35 mined upper and lower limits of pressure cor- responding to the desired upper and lower limits of compression desired for said elements, a plurality of operating members associated with 40 each element, electrical means operated by said pressure responsive members for variably setting said operating members, and means at said sorting station operable by said operating mem- bers for variably setting said stop mechanism.

25. In a compression testing device, in com- bination with means for supporting an element to be tested in compression-testing position, a loading head including a member adapted to be engaged with said element and a fluid pressure device cooperating with said member for applying a predetermined compression stroke to said member, lever means mounting said load- 50 ing head and responsive to variations in resist- ance to compression of elements being meas- 55 ured, a fluid pressure device responsive to the movement of said lever means for developing variations of pressure, and instrumentalities actuated by variations of pressure developed in 60 said last named fluid pressure device for segre- gating tested elements in conformity with their resistance to compression, said last named fluid pressure device including a back pressure cham- 65 ber and an orifice communicating therewith and through which a flow of fluid is maintained and said lever means including a lever on which said head is mounted, means operatively con- 70 nected to said lever for amplifying the move- ment thereof, and a member operated by said amplifying means and disposed in opposition to said orifice to vary the pressure in said chamber by movement toward and away from said orifice.

26. In a compression testing device, in com- bination with means for supporting an element to be tested in compression-testing position, a

loading head including a member adapted to be engaged with said element and a fluid pressure device cooperating with said member for applying a predetermined compression stroke to said member, lever means mounting said loading head and responsive to variations in resistance to compression of elements being measured, a fluid pressure device responsive to the movement of said lever means for developing variations of pressure, and instrumentalities actuated by variations of pressure developed in said last named fluid pressure device, said instrumentalities including a plurality of pressure responsive chambers in communication with said second named fluid pressure device, operating means associated with and respectively operable by said chambers, and means for setting said last named means to respond to upper and lower predetermined pressures in said chambers respectively.

27. In a compression testing device, in combination with means for supporting an element to be tested in compression-testing position, a loading head including a member adapted to be engaged with said element and a fluid pressure device cooperating with said member for applying a predetermined compression stroke to said member, lever means mounting said loading head and responsive to variations in resistance to compression of elements being measured, a fluid pressure device responsive to the movement of said lever means for developing variations of pressure, instrumentalities activated by variations of pressure developed in said last named fluid pressure device for segregating tested elements in conformity with their resistance to compression, said first named member being adjustable with respect to said head to conform with varying free lengths of the elements being measured, and means at the measuring position for engaging an element and said supporting means with said member and adjusting said member with respect to said head before the compression stroke is applied to said element.

28. In a compression testing device, in combination with means for supporting an element to be tested in compression-testing position, a loading head including a member adapted to be engaged with said element and a fluid pressure device cooperating with said member for applying a predetermined compression stroke to said member, lever means mounting said loading head and responsive to variations in resistance to compression of elements being measured, a fluid pressure device responsive to the movement of said lever means for developing variations of pressure, said last named fluid pressure device including a back pressure chamber and an orifice in communication therewith and through which a flow of fluid is maintained and said lever means having a member operable thereby and cooperating with said orifice for varying the back pressure developed in said chamber, separate pressure responsive chambers in communication with said back pressure chamber and respectively operable by different predetermined pressures developed in said back pressure chamber, and instrumentalities actuated by said chambers for effecting segregation of elements in conformity with their resistance to compression.

29. In a compression testing device, in combination with means for supporting an element to be tested in compression-testing position, a

loading head including a member adapted to be engaged with said element and a fluid pressure device cooperating with said member for applying a predetermined compression stroke to said member, lever means mounting said loading head and responsive to variations in resistance to compression of elements being measured, a fluid pressure device responsive to the movement of said lever means for developing variations of pressure, said last named fluid pressure device including a back pressure chamber and an orifice in communication therewith and through which a flow of fluid is maintained and said lever means having a member operable thereby and cooperating with said orifice for varying the back pressure developed in said chamber, separate pressure responsive chambers in communication with said back pressure chamber and respectively operable by different predetermined pressures developed in said back pressure chamber, means associated with said chambers for adjusting the upper and lower pressures to which said chambers will respond, and instrumentalities actuated by said chambers for effecting segregation of elements in conformity with their resistance to compression.

30. In a compression testing device, a loading head including a member adapted to be engaged with an element to be tested and a fluid pressure device cooperating with said member for applying a predetermined compression stroke to said member, means mounting said loading head and movable proportionately to variations in resistance to compression of the elements being measured, a second fluid pressure device including means operated by said last named means for developing a back pressure in said device proportionate to the movement of said last named means, sorting means for said tested elements selectively movable to a plurality of sorting positions, a plurality of pressure responsive chambers in communication with said second fluid pressure device and selectively operable by varying pressures therein and separate means actuated by each of said pressure responsive chambers and controlling the movement of said sorting means.

31. In a compression testing device, a loading head including a member adapted to be engaged with an element to be tested and a fluid pressure device cooperating with said member for applying a predetermined compression stroke to said member, means mounting said loading head and movable proportionately to variations in resistance to compression of the elements being measured, a second fluid pressure device including means operated by said last named means for developing a back pressure in said device proportionate to the movement of said last named means, a plurality of pressure responsive chambers in communication with said second fluid pressure device and selectively operable by varying pressures therein, sorting means for said tested elements selectively movable to a plurality of sorting positions, means for variably setting said pressure responsive chambers to respond to different pressures developed in said second fluid pressure device, and separate means actuated by each of said pressure responsive chambers and controlling the movement of said sorting means.

32. In a machine for sorting elements according to different resistances to compression, in combination with a plurality of conveyors for feeding sorted elements out of the machine, in-

dexing means for intermittently advancing elements to be sorted to a weighing station and thereafter to a sorting station, a single transporting arm mounted for oscillation between the sorting station and the conveyors, means for operating said arm for picking up elements sequentially from said indexing means and swinging said elements over said conveyors, stop mechanism associated with said last named means and operable for aligning said transporting arm with a selected one of said conveyors, and means for varying the setting of said stop mechanism in response to different compression resistivity in said elements.

LOUIS M. PUSTER.
